UNITED STATES PATENT OFFICE

GERHARD DANKER, OF ORADELL, NEW JERSEY, ASSIGNOR TO GRANDOLIER LIGHTING
FIXTURE CO., OF BROOKLYN, NEW YORK

DESIGN FOR A TABLE LAMP OR ARTICLE OF SIMILAR NATURE

Application filed April 26, 1930. Serial No. 35,395. Term of patent 3½ years.

To all whom it may concern:

Be it known that I, GERHARD DANKER, a citizen of Germany, residing in Oradell, in the county of Bergen and State of New Jersey, have invented a new, original, and ornamental Design for a Table Lamp or Article of Similar Nature, of which the following is a specification, reference being had to the accompanying drawing, forming a part thereof.

Fig. 2 is a side elevational view thereof.

I claim:

The ornamental design for a table lamp or article of similar nature, as shown.

In testimony whereof I affix my signature.

GERHARD DANKER.
